CLAIM

The ornamental design for a dumbbell, as shown and described.

DESCRIPTION

FIG. 1 shows a front perspective view of a dumbbell in accordance with the present design;

FIG. 2 shows a front elevation view of the dumbbell of FIG. 1;

FIG. 3 shows a rear elevation view of the dumbbell of FIG. 1;

FIG. 4 shows a top view of the dumbbell of FIG. 1;

FIG. 5 shows a bottom view of the dumbbell of FIG. 1; and,

FIG. 7 shows a right elevation view of the dumbbell of FIG. 1. The broken lines illustrate portions of the dumbbell that form no part of the claimed design.

1 Claim, 6 Drawing Sheets
